UNITED STATES PATENT OFFICE.

JOHN WAJER AND OTTO W. HOPP, OF CHICAGO, ILLINOIS.

TOY DUMP WAGON.

Application filed March 17, 1924. Serial No. 699,692.

To all whom it may concern:

Be it known that we, JOHN WAJER and OTTO W. HOPP, citizens of the United States, residing at Chicago, in the county of Cook and State of Illinois, have invented certain new and useful Improvements in Toy Dump Wagons, of which the following is a specification, reference being had to the accompanying drawings and to the reference characters marked thereon, which form a part of this specification.

This invention relates to toy dump wagons and consists in the devices and combination of devices illustrated and herein described and claimed.

In the accompanying drawings:

Fig. 1 illustrates, in side elevation, a toy dump wagon embodying our invention.

Fig. 2 illustrates the same in an end elevation, showing in dotted lines the position of the body when tilted.

Fig. 3 is a transverse, vertical, sectional view of the same, showing the body in tilted position with the side of the body raised, the section being taken in the plane of the dotted line 3-3 of Fig. 1, looking in the direction indicated by the arrows.

The toy comprises a frame on wheels, a pivoted body portion pivotally mounted on the frame and adapted to be tilted from and to be restored to the normal position, and means for automatically actuating the locking means after the tilted body has been restored to the normal position.

The frame is formed of two longitudinally extending side members on edge, 1, 2, and two intermediate end members 3, 4, and one or more spacing and strengthening members 5, located intermediate the ends 3 and 4. The side and end members are preferably made of wood as shown, and the members 3, 4 and 5 are of greater height than width so as to project above the top margins 6 of the side members 1 and 2.

Near each end of the frame is a wire axle 6 which passes through the side members 1 and 2 and projects outwardly to support the wheels 7 mounted thereon, and suitably held by cotter pins 8. A pivot bar 9 extends lengthwise of the frame, being supported by the ends 3 and 4 and the intermediate spacer members 5. The bar 9 as shown is located near the top margins of the end members and centrally thereof and forms a support for the wagon body.

The body of the wagon comprises a bot-

tom board 10, end boards 11 and 12, and two sides 13 and 14. The bottom 10 is provided with three downwardly projecting and transversely extending strengthening rib members 15, one of which is located between the upright members 5, 5, of the frame. The bar 9 extends through the rib members 15 and the bar not only supports the body but acts as a pivotal connection whereby the body may be tilted.

At each end of the wagon I provide a hinge strap member 16, 16, upon the side member 14, which straps are bent around the end members 11 and 12 and pivotally secured thereto at 17. One of the straps 16 is extended to form a handle 18. By this arrangement it will be readily seen that by pulling the handle 18 downwardly (towards the wheels 7) the side member 14 will be swung upon the hinge or pivotal connection 17 and assume the raised position shown in Fig. 3. Also that when so raised and the body tilted, any sand or other object which may have been in the body will be free to slide off the inclined floor 10.

The body will normally be held in the horizontal position shown in Figs. 1 and 2, with the bottom board 10 seated upon the horizontal part 19 of the top margins of the members 3, 4 and 5. Said top margins are also provided with portions 20 which incline downwardly on the side of the body member 14, which inclined parts 20 support the bottom 10 when the body is tilted, as shown in Fig. 3.

To hold the body in the normally un-tilted position, a movable stop arm 21 is movably mounted on the member 4 at a point between the center and one edge of said member 4, as clearly shown in Fig. 2. When the body is to be tilted, this arm 21 is moved toward the center of the member 4 (i. e. away from the direction of tilt) and thus out of contact with the bottom 10, as shown by the dotted lines in Fig. 2, whereupon the bottom 10 will be permitted to rest upon the inclined margins 20.

The arm 21 is formed by bending upwardly, a wire rod 22, which latter is rotatively mounted upon the members 4 and 5. A tension spring 23 attached to the rod 22 bears against the inside of the side frame member 1 and exerts its tension to rotate the rod 22. Thus when the wagon body is manually returned from its tilted position

shown in Fig. 3 to its normal position shown in Figs. 1 and 2, the spring 23 by rotating the rod 22 will swing the arm 21 and cause the latter to again engage the bottom 10 of the wagon body and hold it in the horizontal position.

5 A handle 24 on the arm 21 facilitates its operation. An ordinary staple 25 driven into the member 4 about the arm 21 will limit 10 the extent of the swinging movement of said arm. A similar staple 26 may serve as a means of attaching a cord or other device for hauling the toy wagon about.

We claim as our invention:

15 1. A toy dump wagon comprising a frame on wheels, supporting members extending above the top of the frame, horizontal and inclined top margins on said supporting members, a pivot bar in said supporting 20 members extending lengthwise of the frame, a wagon body swingingly mounted on said pivot bar and a hinged side member to the body.

25 2. A toy dump wagon comprising a frame having wheels, supporting members extending above the frame, a centrally located pivot rod in said members extending longitudinally of the frame, a wagon body, rib members on the body hingedly mounted on 30 the pivot rod and resting normally on aligned top margins of the said supporting members, the latter being cut away to form inclined, aligned supports for the body when tilted about said pivot bar, a movable side to the wagon body, straps on the movable side extending around to the body ends and pivotally connected thereto, one of said 35 straps being provided with a handle to actuate said pivotally mounted side member.

40 3. A toy dump wagon comprising a frame having wheels, supporting members extending above the frame, a centrally located pivot rod in said members extending longitudinally of the frame, a wagon body, rib members on the body hingedly mounted on

the pivot rod and resting normally on aligned top margins of the said supporting members, the latter being cut away to form inclined, aligned supports for the body when tilted about said pivot bar, a movable side to the wagon body, straps on the movable side extending around to the body ends and pivotally connected thereto, one of said straps being provided with a handle to actuate said pivotally mounted side member, movable means for holding the body in its untilted position, and located adjacent to the said handle.

45 4. A toy dump car comprising a frame having transverse supports, four wheels upon which the frame is mounted, horizontal and inclined supporting surfaces on the said supports, a centrally located longitudinally extending pivot bar on said supports, a wagon body having one of its sides movably secured by pivot straps to the body ends, a rotatable rod on the frame projecting through one end member thereof and bent upwardly at its projecting end to form 50 an arm stop, said arm stop contacting with and supporting the wagon bottom at one side of its point of pivotal connection with the said pivot bar and movable out of contact with the body when the latter is tilted to rest upon said inclined surfaces, a spring 55 attached to said rotatable rod and adapted to cause the latter to rotate when released, a stop for limiting the movement of the arm stop and handles for manually operating 60 said stop arm and said hinged body member.

In testimony, that we claim the foregoing as our invention, we affix our signatures, in the presence of two witnesses this 12th day 65 of March, 1924.

JOHN WAJER.
OTTO W. HOPP.
